Term of patent 14 years

Int. Cl. D9—03

U.S. Cl. D9—193

FIG. 3

FIG. 1 is a perspective view of a combined razor, razor blade cartridge dispenser and holder therefor showing my new design, the razor being positioned on top of the holder, and the dispenser being positioned beneath an elongated portion of the holder;

FIG. 2 is a side elevational thereof; and

FIG. 3 is a bottom plan view thereof.

The razor and the holder are each symmetrical about a vertical plane, as viewed in FIG. 2, extending through their respective longitudinal axes.

I claim:

The ornamental design for a combined razor, razor blade cartridge dispenser and holder therefor, as shown and described.
